UNITED STATES PATENT OFFICE

120,510

DESIGN FOR A COMBINATION CAMERA AND ILLUMINATING DEVICE

Albert J. Kunze, Cleveland, Ohio

Application February 16, 1940, Serial No. 90,318

Term of patent 14 years

To whom it may concern:

Be it known that I, Albert J. Kunze, a citizen of the United States, residing at Cleveland, in the county of Cuyahoga and State of Ohio, have invented a new, original, and ornamental Design for a Combination Camera and Illuminating Device, of which the following is a specification, reference being had to the accompanying drawings, forming a part thereof.

In the drawings, Fig. 1 is a perspective view

of my combination camera and illuminating device; Fig. 2 is a plan thereof; Fig. 3 is a side elevation looking at the opposite side from that appearing in Fig. 1; Fig. 4 is a rear elevation; Fig. 5 is a front elevation.

I claim:

The ornamental design for a combination camera and illuminating device, substantially as shown.

ALBERT J. KUNZE.
